SAFETY LOCK

Application filed December 17, 1928, Serial No. 326,532, and in Switzerland January 4, 1928.

The present invention relates to safety locks of the kind having a drop latch engaged into a striking plate and a handle which in order to lift the latch must first be turned for a certain number of steps alternately in a clockwise and an anticlockwise direction before it can catch said latch so as to lift and release it.

The annexed drawings represent as an example one working form of the object of the invention.

The Fig. 1 shows the lock and the latch in a front elevation.

Fig. 2 is a cross section of the same.

The Figures 3 and 4 represent the first an inside view of the lock having the front cover removed and the second is a front view of the bottom of the casing.

The Figures 5, 6 and 7 are front view, end view and back view of a disk carrying the coupling members between the latch and the handle.

The casing 1 of the lock is cylindrical and comprises a bottom 2, an annular body 3 and a cover 4. A shaft 6 having a handle 5 secured thereto is rotatably held in central holes of the bottom and the cover and is rigidly connected to a disk 7 arranged between the cover and the bottom. This disk 7 has two segmental parts cut off on two diametrically opposite sides and on two parallel lines, a smaller cut 21 and a larger cut 22. In the body of the disk is slidably lodged a short pointed pin 8 projecting normally under the effect of a spring into the smaller cut 21 of the disk so as to be transiently engaged into the notches 9 provided inside of the annular body 3. The said notches mark the steps which are to be made when turning the button 5. This button has on its circumference as many circular notches 9¹ as there are notches 9 and besides a guiding mark 20 on the side facing the lock. Another pin 10 is slidably lodged in the body of the disk 7 but not in the same vertical plane perpendicular to the axis and in a stepped part of said disk of smaller diameter. Said pin carries two cross-pegs whereof the one 12 is guided within a slot on the back side of the disk 7 while the other peg

11 is guided in another slot on the front side of said disk. The sliding pin 10 is under the effect of a spring 13 and is normally maintained by this spring in such a position that the peg 12 is near the periphery of the disk 7 while the other peg 11 is near the center of the disk. At its one end this pin 10 is provided with a nose 14 which projects over the periphery of that part of the disk 7. This nose 14 is in the path of another nose 15 fixed to the annular body 3. Now when shaft 6 is turned by means of the button 5 the two noses will meet and pin 10 be pushed back displacing thereby also the pegs 11 and 12.

The bolt 16 of the lock is located between disk 7 and cover 4 and is held loose on the shaft 6. It touches the surface of the disk, but is recessed on a certain part 17 so that the peg 11 may pass beneath it when the disk is rotated. While the length of peg 12 must be sufficient for having this peg guided within the grooves 18, which are described hereafter, and while this peg 12 has to travel gradually towards the center the peg 11 will move outwardly. The length of this peg 11 is so chosen that when the disk 7 is rotated the peg will pass freely through the recessed portion 17 of the latch as long as it has not yet reached its extreme outward position. When in this position however it will meet the non-recessed portion of the latch and be able to move this latch so as to lift it.

On the inside of the bottom wall 2 of the casing 1 a number of circular grooves are arranged concentrically into which are fixed springy steel blades 18 leaving canals between them available as guides for the peg 12. The said blades are not extended over the whole circumference of the grooves but only on certain sectors corresponding in length to a certain number of the steps marked by the notches 9. Besides a certain leg 19 of each of these blades is flexible and touches the next outer blade so as to block the passage between the two respective blades. The whole of the blades constitutes a labyrinth having passages the length of which expressed in numbers of steps corresponds to a combination of numerals the knowledge of which allows to open the lock.

The working of the latch by means of the handle 5 is as follows:

The handle is first turned into a position determined by the guiding mark 20 and 5 known only by the person initiated into the secret. This position is given in the Figures 3 and 4 and shows the nose 14 touching the nose 15 from underneath. The back wall 2 considered as a dial has been divided in eight 10 sectors by means of radial incisions and corresponding with the division of the notches 9.

The shaft 6 is now turned to the left in Fig. 4 as indicated by the arrows first in the direction of the outer arrow. By this movement 15 nose 14 will be pushed back by nose 15 so as to bring peg 12 before the entrance of the outer passage. While continuing the turning movement a slight resistance will be felt every time when the pin 8 passes the 20 notches marking the steps of the movement. Having passed four steps that is as many steps as is indicated by the first numeral of the combination number the shaft is turned backwards to the right as indicated by the 25 median arrow and is turned 4 steps that is as many steps as indicated by the second numeral. During this backward movement peg 12 will travel in the outermost passage but one because at the end of the outermost passage 30 it had pushed the leg 19 aside and when returning had been directed by the same leg into the next passage nearer to the center. Thus by turning shaft 6 alternately forward and backward every time for the number of steps 35 prescribed by the combination number the peg 12 will move with the fourth movement into the innermost passage next to the center and next to the outlet of the blade system but then to the contrary peg 11 will have

40 moved the farthest from the center and have passed beyond the recessed part 17 of the latch 16 so that with the second backwards movement that is with the fourth turning movement of the shaft during which peg 12 is maintained 45 near the center, the latch will be caught at the non recessed portion by the peg 11 which has travelled now far enough outwardly in a radial direction. By a continued turn of the handle the latch will be lifted and released 50 from the striking plate, which has not been represented in the drawings. In this case therefore as shown in Fig. 4 the combination number will be 4432. This number besides the knowledge of the starting point must

55 be known by those who want to open this lock. It will be easily understood that instead of arranging the lock with four blades and for a combination number having four numerals the number of blades could be increased or be 60 decreased and that also the number of divisions on the bottom plate 2 could be more or less than eight and also the position of the guiding mark 20 could be changed.

If it is wanted to lock the latch again shaft 65 6 has to be turned several times backward

again. Then the peg 11 will come to interrupted parts of the blades whereby under the effect of spring 13 pin 10 will at once assume again its initial position of rest. Thereby the latch 16 is rendered again independent from any further movement of the button 5.

What we claim as new is:

1. In a safety lock and in combination a casing having an annular rim provided with an inside division marked with notches, a projecting shaft with a handle arranged concentrically to said division and rotatable in said casing and constituting the locking and unlocking means, a similar division like the first and a guiding mark provided on said handle, a rotatable member fitting said annular rim and secured to said shaft, a short pointed pin lodged resiliently in said member and adapted to mark the steps taken by said member while passing said notches of the rim, a slidable pin carrying two cross pegs projecting on opposite sides, said pin being resiliently mounted in said member having a nose projecting beyond the periphery of the member, a stationary nose secured to the said rim and projecting in the path of the first nose, a latch held loose on the shaft close beside the said member and having a recessed part on the side of this member in the path of the respective peg of said slidable pin and a labyrinth of springy blades arranged concentrically to the shaft and forming a number of passages for the second peg on the bottom of the casing and arranged so as to constitute a guide for said peg and for the sliding pin in order to bring the first peg in contact with the non recessed part of the latch so as to release it from its catch.

2. In a safety lock and in combination a casing having an annular rim, a projecting shaft having a handle located concentrically to said rim and rotatable in said casing and constituting the locking and unlocking means, a rotatable member fitting said annular rim and rigidly secured on said shaft, a pin fitted slidably in said member and having a nose projecting beyond the periphery of the member, a spring arranged so as to hold said pin in an initial position of rest, two cross pegs fixed to said pin and projecting at opposite ends and on opposite sides to the outside of said rotatable member, a recessed latch held radially and loose on the shaft close beside the said member in the path of one of the pegs of the slidable pin, the recessed part of the latch limiting the possibility of engagement between latch and pin to the most extended position of the latter, a labyrinth of springy blades disposed on a certain sector only of the casing and forming a number of concentric passages of a limited length for the second peg and constituting a guide for this peg and for the sliding pin in order to bring the first peg in its most extend-

ed position in contact with the non recessed part of the latch and to release this latch from its catch.

5 In testimony whereof we affix our signatures.
